UNITED STATES PATENT OFFICE.

FRANK E. WELLMAN, OF KANSAS CITY, KANSAS, ASSIGNOR TO KANSAS CITY GASOLINE COMPANY, OF KANSAS CITY, KANSAS, A CORPORATION OF KANSAS.

METHOD OF DISTILLING HYDROCARBONS.

Application filed June 3, 1922. Serial No. 565,634.

My invention relates to the treatment of hydro-carbon oils, and has special reference to cracking petroleum. It has for its objects the improvement of the methods here-
5 tofore practiced in treating the heavier fractions which are ordinarily separated out and refluxed to the cracking still for re-treatment to produce an increased yield of gaso-
line with a minimum amount of fuel con-
sumed, and to positively control the frac-
10 tions finally delivered to the condenser.

Heretofore the return of condensate to the cracking still has been carried on by direct and simultaneous cooling and running
15 back of the condensed fractions. According-
20 ing to my present invention, however, the return is not direct nor simultaneous with the cooling, but the heavy fractions sepa-
25 rated out are treated in a supplemental still,
30 and after distilling off their lighter compo-
nents are then returned to the cracking still for re-cracking. The operation is a con-
tinuous one, fresh oil being fed in by way
35 of the supplemental still, and the lighter
40 vapors from both the cracking still and the supplemental still being carried through a pipe line containing a pressure retaining valve, to the condenser, where they are finally condensed either at atmospheric pres-
45 sure, or under pressure not exceeding twenty
50 pounds per square inch.

The accompanying drawing is a diagram illustrating one form of apparatus with which my invention may be practiced.

55 In the drawing, 1 indicates the cracking still, 2 the vapor line therefrom to the fractionator 3, having a feed pipe 8, a vapor line 10, and a down pipe 4 into the supplemental still 5, which is connected by vapor
60 line 9 to a supplemental fractionator 6 also connected to the vapor line 10 and thence to a pipe line 12 containing a valve 11 and leading to the condenser 13 from which suitable connection is effected to the storage tank 14. Stills 1 and 5 are heated by furnaces 1^a and 5^a, respectively.

In operation, the cracking still, being filled with hydrocarbon oil to the level marked 15, is heated to approximately 750° F., whereupon vapors pass through the line 2 to the fractionator 3, wherein cooling and condensation of the heavier fractions take place, the lighter vapors passing over and into pipe line 10. The heavy condensate
55 is thrown down and drains through pipe

4 into the supplemental still 5, which is filled to common liquid level 15, maintained through the pipe 7. Heat is applied to the supplemental still 5 and the oil therein is re-distilled at approximately 550° F., the 60 vapors produced passing through pipe 9 and fractionator 6 to pipes 10 and 12, pres-
65 sure being maintained in the system up to valve 11. The vapors are then released through valve 11 and pass through pipe line 65 12 to the condenser, where they are all con-
70 densed under pressure of twenty pounds or less. The process is rendered continuous by supplying fresh oil through supply pipe 8, as the level 15 is lowered by withdrawals. 70

75 The advantages attained by the introduc-
80 tion of supplemental heating thus de-
scribed, will be obvious to those skilled in
the art. In the previous systems referred
85 to, in which simultaneous cooling and re-
fluxing are carried on, rising vapors are
90 constantly carrying and giving up heat to
the condensed and condensing material al-
95 ready in the runback or fractionator, so that
both cooling and heating effects are pro-
100 duced, without control of the resultant tem-
perature to which the reflux is raised on its
journey back to the cracking still. The reflux
105 material merely absorbs whatever heat is
communicated to it in amount depending
110 upon its own weight in proportion to that of
the ascending vapors and the difference in
the temperatures of the two counter flowing
streams.

90 My system on the other hand attains the following pronounced and useful results:

1. Heat is applied to the condensate be-
100 fore its return to the cracking still, under
control of an operator, and its temperature
can therefore be regulated within the
105 necessary limits to secure desired fractions
in the condenser. This cannot be done with
ordinary refluxing.

110 2. The vaporization due to such supple-
mental heating takes place away from and
out of contact with the vapor stream from
the cracking still, whereby adulteration is
115 avoided. Such adulteration or mixing of
high and low boiling fractions in the vapor
line always takes place where the reflux is
through said line.

120 3. The operation of supplemental still 5
results in an increased yield of gasoline, be-
cause all the material that reaches the con-
denser is within the proper boiling range,

instead of only a fraction thereof as by former practice.

I am aware that some changes may be made in the apparatus and detailed operation thus described; and I wish it understood that I contemplate all such changes as fall fairly within the scope of the appended claims.

What I claim is:

- 10 1. The method of treating hydrocarbon oil to produce a lighter hydrocarbon of the same series, which consists in distilling the heavier hydrocarbon in one zone at high cracking temperature and pressure, fractionating all the vapors produced in said first zone in a second zone, conducting off and condensing the vapors from said second or fractionating zone while refluxing to and redistilling the heavier fractions in a third zone at a temperature lower than that in the first cracking zone, separately fractionating in a fourth zone the vapors produced by redistillation in said third zone, conducting off and condensing the light vapors from said fourth zone, returning the heavier fractions from the fourth zone into the third zone, and returning all the heavier fractions from the third zone in liquid phase into the first zone.
- 15 2. The method of treating hydrocarbon oil to produce a lighter hydrocarbon of the same series, which consists in distilling the heavier hydrocarbon in one zone at high cracking temperature and pressure, fractionating all the vapors produced in said first zone in a second zone, conducting off and condensing the vapors from said second or fractionating zone while refluxing to and redistilling the heavier fractions in a third zone at a temperature lower than that in the first cracking zone, separately fractionating in a fourth zone the vapors produced by redistillation in said third zone, conducting off and condensing the light vapors from said fourth zone, returning the heavier fractions from the fourth zone into the third zone, and returning all the heavier fractions from the third zone in liquid phase into the first zone.
- 20 3. The method of treating hydrocarbon oil to produce a lighter hydrocarbon of the same series, which consists in distilling the heavier hydrocarbon in one zone at high cracking temperature and pressure, fractionating all the vapors produced in said first zone in a second zone, conducting off and condensing the vapors from said second or fractionating zone while refluxing to and redistilling the heavier fractions in a third zone at a temperature lower than that in the first cracking zone, separately fractionating in a fourth zone the vapors produced by redistillation in said third zone, conducting off and condensing the light vapors from said fourth zone, returning the heavier fractions from the fourth zone into the third zone, and returning all the heavier fractions from the third zone in liquid phase into the first zone.
- 25 4. The method of treating hydrocarbon oil to produce a lighter hydrocarbon of the same series, which consists in distilling the heavier hydrocarbon in one zone at high cracking temperature and pressure, fractionating all the vapors produced in said first zone in a second zone, conducting off and condensing the vapors from said second or fractionating zone while refluxing to and redistilling the heavier fractions in a third zone at a temperature lower than that in the first cracking zone, separately fractionating in a fourth zone the vapors produced by redistillation in said third zone, conducting off and condensing the light vapors from said fourth zone, returning the heavier fractions from the fourth zone into the third zone, and returning all the heavier fractions from the third zone in liquid phase into the first zone.
- 30 5. The method of treating hydrocarbon oil to produce a lighter hydrocarbon of the same series, which consists in distilling the heavier hydrocarbon in one zone at high cracking temperature and pressure, fractionating all the vapors produced in said first zone in a second zone, conducting off and condensing the vapors from said second or fractionating zone while refluxing to and redistilling the heavier fractions in a third zone at a temperature lower than that in the first cracking zone, separately fractionating in a fourth zone the vapors produced by redistillation in said third zone, conducting off and condensing the light vapors from said fourth zone, returning the heavier fractions from the fourth zone into the third zone, and returning all the heavier fractions from the third zone in liquid phase into the first zone.
- 35 6. The method of treating hydrocarbon oil to produce a lighter hydrocarbon of the same series, which consists in distilling the heavier hydrocarbon in one zone at high cracking temperature and pressure, fractionating all the vapors produced in said first zone in a second zone, conducting off and condensing the vapors from said second or fractionating zone while refluxing to and redistilling the heavier fractions in a third zone at a temperature lower than that in the first cracking zone, separately fractionating in a fourth zone the vapors produced by redistillation in said third zone, conducting off and condensing the light vapors from said fourth zone, returning the heavier fractions from the fourth zone into the third zone, and returning all the heavier fractions from the third zone in liquid phase into the first zone.

zone at a temperature lower than that in the first cracking zone, separately fractionating in a fourth zone the vapors produced by redistillation in said third zone, conducting off and condensing the light vapors from said fourth zone, returning the heavier fractions from the fourth zone into the third zone, and returning all the heavier fractions from the third zone in liquid phase into the first zone, by gravity, the pressure in both the first and third zones being maintained equal.

3. The method of treating hydrocarbon oil to produce a lighter hydrocarbon of the same series, which consists in distilling the heavier hydrocarbon in one zone at high cracking temperature and pressure, fractionating all the vapors produced in said first zone in a second zone, conducting off and condensing the vapors from said second or fractionating zone while refluxing to and redistilling the heavier fractions in a third zone at a temperature lower than that in the first cracking zone, separately fractionating in a fourth zone the vapors produced by redistillation in said third zone, conducting off and condensing the light vapors from said fourth zone, returning the heavier fractions from the fourth zone into the third zone, and returning all the heavier fractions from the third zone in liquid phase into the first zone.

In testimony whereof I hereunto affix my signature.

FRANK E. WELLMAN.
